(57) **CLAIM**

The ornamental design for a notebook computer with flippable keyboard, as shown and described.

DESCRIPTION

FIG. 1 is a perspective view of a notebook computer with flippable keyboard showing a first embodiment of our new design;

FIG. 2 is a front view of the first embodiment thereof;

FIG. 3 is a rear view of the first embodiment thereof;

FIG. 4 is a left side view of the first embodiment thereof;

FIG. 5 is a right side view of the first embodiment thereof;

FIG. 6 is a top view of the first embodiment thereof;

FIG. 7 is a bottom view of the first embodiment thereof;

FIG. 8 is an enlarged view of the portion, labeled '8' of FIG. 1;

FIG. 9 is an enlarged view of the portion, labeled '9' of FIG. 1;

FIG. 10 is an enlarged view of the portion, labeled '10' of FIG. 2;

FIG. 11 is an enlarged view of the portion, labeled '11' of FIG. 4;

FIG. 12 is a perspective view of the first embodiment thereof in a state of use with the keyboard flipped;

FIG. 13 is a left side view of the first embodiment thereof in a state of use with the keyboard flipped;

FIG. 14 is a right side view of the first embodiment thereof in a state of use with the keyboard flipped;

FIG. 15 is a bottom view of the first embodiment thereof in a state of use with the keyboard flipped;

FIG. 16 is an enlarged view of the portion, labeled '16' of FIG. 12;

(Continued)

FIG. 17 is an enlarged view of the portion, labeled '17' of FIG. 13;
 FIG. 18 is a perspective view of a notebook computer with flippable keyboard showing a second embodiment of our new design;
 FIG. 19 is a front view of the second embodiment thereof;
 FIG. 20 is a rear view of the second embodiment thereof;
 FIG. 21 is a left side view of the second embodiment thereof;
 FIG. 22 is a right side view of the second embodiment thereof;
 FIG. 23 is a top view of the second embodiment thereof;
 FIG. 24 is a bottom view of the second embodiment thereof;
 FIG. 25 is an enlarged view of the portion, labeled '25' of FIG. 18;
 FIG. 26 is an enlarged view of the portion, labeled '26' of FIG. 18;
 FIG. 27 is an enlarged view of the portion, labeled '27' of FIG. 19;
 FIG. 28 is an enlarged view of the portion, labeled '28' of FIG. 21;
 FIG. 29 is a perspective view of the second embodiment thereof in a state of use with the keyboard flipped;
 FIG. 30 is a front view of the second embodiment thereof in a state of use with the keyboard flipped;
 FIG. 31 is a left side view of the second embodiment thereof in a state of use with the keyboard flipped;
 FIG. 32 is a right side view of the second embodiment thereof in a state of use with the keyboard flipped;
 FIG. 33 is a bottom view of the second embodiment thereof in a state of use with the keyboard flipped;
 FIG. 34 is an enlarged view of the portion, labeled '34' of FIG. 29; and,
 FIG. 35 is an enlarged view of the portion, labeled '35' of FIG. 31.

The dashed broken lines illustrate portions of the notebook computer with flippable keyboard and form no part of the claimed design. The dot-dash broken lines define the bounds of the claimed design and form no part thereof.

1 Claim, 35 Drawing Sheets
